UNITED STATES PATENT OFFICE

OSCAR V. PAYNE, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS

WEFT DETECTOR AND BOBBIN THEREFOR

Application filed August 14, 1930. Serial No. 475,243.

This invention relates to weft detectors for bobbins, supplied with weft having electric current carrying properties, such as metallic thread, and it is the general object of the invention to rely upon non-completion of an electric circuit when the weft is exhausted to effect a change in the operation of the loom.

When weft of a metallic nature is carried by a shuttle it is frequently desirable to stop the loom either at or prior to weft exhaustion. This result is preferred to weft replenishment because of the nature of the weft although the invention set forth herein is equally applicable to looms where automatic weft replenishment may follow weft exhaustion. Some forms of metallic yarn employ a thin layer of metal such as gold or silver wound spirally on a core of silk thread. The weft therefore presents an electric current conducting surface and it is an important object of my present invention to employ an electrically operating weft detector which will act by a current flowing through the weft to disable change inducing mechanism, the parts being so arranged that when weft is absent the carrier which is an insulator will prevent establishment of a circuit and cause the change mechanism to operate.

With these and other objects in view which will appear as the description proceeds, my invention resides in the combination and arrangement of parts hereinafter described and set forth in the claims.

In the accompanying drawing wherein a convenient embodiment of my invention is set forth,

Fig. 1 is a top plan view of a portion of a loom having my invention applied thereto,

Fig. 2 is a top plan view on an enlarged scale of certain of the structure shown in Fig. 1, the shuttles being shown in section,

Fig. 3 is a vertical section on line 3-3 of Fig. 2, and

Fig. 4 is a plane view on an enlarged scale

of parts shown in Fig. 1, the solenoid being shown partly in section.

Referring to Fig. 1, I have shown a loom frame 10 and a lay 11 provided with a shuttle box 12 to receive a shuttle S. The usual binder 13 may be provided and the shuttle is provided with a bobbin B on which is wound a mass of weft W unlike the usual weft in that it has capacity for conducting electric current. The weft may be metallic and made of gold or silver or any other desired metal.

A bracket 14 is secured to the side of the loom and has an arm 15 provided with a vertical slot 16 in which reciprocates a block 17 to the upper end of which is pivoted a floating actuator lever 18. The left hand end of said lever as shown in Fig. 1 may be connected to an upwardly extending rod 19, while the right hand end thereof is mounted to reciprocate in a vertical slot 20 formed in a horn 21 projecting from the bracket 14.

In the operation of the loom when a weft magazine is used the block 17 is caused to reciprocate during a two-pick cycle, moving down from a normal intermediate position when the shuttle is on the near side of the loom, and moving upwardly from such normal position when the shuttle is on the opposite side of the loom. When the loom is to be stopped to permit hand replenishment, the upward movement when the shuttle is on the opposite side of the loom will be unnecessary.

An extension of the bracket 14 has mounted thereon the weft detecting mechanism D having a body 22 formed of insulating material and secured to the bracket by means of bolts 23. There are two parallel elongated holes extending longitudinally of the body 22, designated at 24, the front end of each hole being threaded as at 25 and the rear end being reduced as at 26. Slidably mounted in each of these bores or holes is a metallic feeler wire 27 having a collet 28 slidable in the large part of the bore 24 and

limited as to rearward movement by the shoulder 29 which separates the large and small parts of the bore. A small compression coil spring 30 lies around each wire and has the rear end thereof in pressing engagement with the shoulder 28. The forward end of the spring bears against a stud 31 which is threaded into the portion 25 and has a hole therein 32 through which the feeler wire 27 extends.

Associated with each of the studs 31 is a contact plate 33 through which extends a clamping screw 34 to hold a terminal 35 in contact with the plate by means of a lock washer 36. The head of the stud is formed as a nut 37 and accords means for tightening the stud in the body 22. Because of the material of the body 22, the wires are insulated from each other and the plates 33 are out of contact at all times.

The detecting mechanism D is illustrated as a means for passing current through the weft W, but I wish it to be understood that I am not limited to this particular type of detector, inasmuch as my invention may be used with any form of electrical detector wherein a circuit is established through the weft.

Referring to Figs. 1 and 4, it will be seen that I have mounted a solenoid 40 on the bracket 14 in fixed relation with respect thereto and have provided the same with a plunger or controller pin 41 having a collet 42 thereon to engage a portion of the horn 21. The plunger or controller has a part which extends beyond the collet to lie normally under the right hand end of the actuator lever 18. A light compression spring 43 lies between the collet and the solenoid and tends to hold the controller normally under the actuator lever as shown in Fig. 4, but said spring is sufficiently weak to be overpowered by the magnetic attractive force of the solenoid on the controller, which is of course made of magnetic material.

Under normal conditions the spring 43 will hold the collet in rearmost position with the controller under the actuator. As the lay advances with the shuttle on that side thereof adjacent the described mechanism, wires 27 will have contact with a sufficient supply of weft W so that current will flow through the following circuit; source of electric power 50, wire 51, solenoid 40, wire 52, left hand terminal 35 and corresponding wire 27, the metallic weft on the bobbin, the other wire 27 and its corresponding terminal 35, wire 53, back to the battery. Current flowing in this circuit will energize the solenoid and cause the same to move the controller forwardly to the dotted line position shown in Fig. 4. The block 17 moves downwardly while the circuit is closed and the rod 19 is therefore left unmoved.

When insufficient weft is present, however, the circuit previously traced will not be closed because the detector wires will not be electrically connected, the bobbin in this instance being formed of insulating material to accomplish this result. The spring 43 will hold the controller under the actuator lever so that as the block 17 descends said controller becomes a pivot for the actuator lever 18 to cause depression of the rod 19.

It is deemed sufficient for the purposes of the present invention to state that when rod 19 is moved downwardly it will bring about a change in the operation of the loom. This change may be in the nature of weft replenishment, in which case the rod 19 will act in a manner similar to the corresponding rod shown in Patent No. 1,030,748. If loom stoppage is desired depression of rod 19 may be rendered effective to control any one of the well-known loom stopping devices to arrest motion of the loom so that weft may be manually replenished.

From the foregoing it will be seen that I have provided a very simple means for effecting a change in the operation of a loom having metallic weft by causing the latter to establish a current which disables mechanism normally operative to bring about a change in the loom, absence of the weft permitting the mechanism to perform its normal function. It is sufficient if the controller tends to stop the loom or otherwise alter its operation at that time only when the previously traced circuit is closed. The usual practice in connection with electrical weft detectors is to keep the yarn engaging electrodes corresponding to wires 27 insulated from each other so long as a sufficient supply of weft is present, depletion of the weft uncovering the current conducting surface which electrically connects the electrodes. The invention set forth herein operates on the opposite principle and requires that the bobbin on which the current conducting weft is wound shall be so made that the part thereof which engages the feeler fingers or lies opposite them will prevent the flow of current. The usual wooden or paper bobbins or cops will accomplish this result without additional treatment and the detector may be of the usual electrical type where a circuit is closed within the shuttle across the feeler electrode. The control mechanism is very well-known, being the same as that which is embodied on practically all multicolor weft replenishing looms and operating in the same general manner.

Having thus described my invention it will be seen that changes and modifications may be made therein by those skilled in the art without departing from the spirit and scope of the invention and I do not wish to be limited to the details herein disclosed, but what I claim is:

1. In a loom operating with a wound mass of electric current conducting weft, electro-magnetic means to effect a change in the operation of the loom and including an electrical detector to contact with the weft, said means acting to effect a change in the operation of the loom when the weft is depleted and incapable of conducting current from the detector.
2. In a loom operating with a wound mass of electric current conducting weft, means tending at a given point in the cycle of the loom to effect a change in the operation of the loom, and an electro-magnetically actuated device dependent upon a flow of electric current through the weft at said given point to render said means ineffective to change the operation of the loom.
3. In a loom operating with a wound mass of electric current conducting weft, means normally operative to effect a change in the operation of the loom, and an electro-magnetic device to be energized by electric current flowing through the weft and render said means ineffective to change the operation of the loom.
4. In a loom operating with a wound mass of electric current conducting weft, means tending at a given point in the cycle of the loom to effect a change in the operation of the loom, and an electro-magnetic device to be energized by electric current flowing through the weft and render said means ineffective to change the operation of the loom.
5. In a loom operating with a weft carrier formed of insulating material on which is wound a mass of weft having electric current conducting properties, mechanism normally effective to cause a change in the loom, and electro-magnetic means dependent upon the flow of current through the weft to render said means inoperative.
6. In a loom operating with a weft carrier formed of insulating material on which is wound a mass of weft having electric current conducting properties, electro-magnetically controlled means dependent upon inability of electric current to flow through the bobbin due to weft absence to effect a change in the operation of the loom.
7. In a loom operating with a weft carrier formed of insulating material on which is wound a mass of weft having electric current conducting properties, electro-magnetic means dependent upon the flow of electric current through the weft to maintain loom operation and effective when current fails to flow due to weft exhaustion to cause a change in the operation of the loom.
8. In a loom, a weft carrier formed of insulating material, a mass of electric current conducting weft on the carrier, an electric feeler to engage the weft and carrier, and electro-magnetically actuated means

controlled by the feeler to effect a change in the operation of the loom, current flowing through the weft from the feeler rendering said means ineffective to stop the loom and failure of current to flow by reason of contact between the carrier and feeler causing said means to effect a change in the operation of the loom.

9. In a loom, a weft carrier of insulating material, a wound mass of weft on said carrier having electric current conducting properties, an electrical weft detector positioned to engage both the weft and the carrier, and means controlled by the detector and dependent upon the inability of current to flow therefrom to the weft due to absence of the latter to effect a change in the operation of the loom.

10. In a loom, a weft carrier having a surface of insulating material, a wound mass of weft on said carrier having electric current conducting properties and normally covering said surface, an electrical weft detector to engage both the weft and the surface, means normally operative to stop the loom, said means being rendered inoperative when current can flow from the detector to the weft due to a sufficient presence of the latter and said means being effective to stop the loom when the detector engages the surface and is out of electric contact with the weft.

11. In a loom, a source of electric power, an electro-magnetically operated controller for the loom, a wound mass of electric current conducting weft, and means to determine the operation of the controller and dependent upon ability thereof to conduct current from the source through the weft to the controller.

In testimony whereof I have hereunto affixed my signature.

OSCAR V. PAYNE.
